UNITED STATES PATENT OFFICE.

THOMAS B. WRIGHT, OF CINCINNATI, OHIO.

MAIL BOX.

Application filed February 18, 1924. Serial No. 693,476.

The object of my invention is to make a cheap, convenient, simple, and highly efficient, serviceable mail box, which shall be made of a few parts.

5 My invention belongs to that class of mail boxes which is generally used by individuals in receiving mail at their home, factory, or other places and is suspended at some convenient point so that the mail carrier can 10 deposit the mail therein.

Mail boxes of this class are usually defective in construction, especially the cheaper ones, and allow the rain, snow, and moisture to penetrate the same on account of the 15 joints or other unsuitable construction. Boxes of this character often tear the mail when it is inserted, or extracted therefrom, on account of the peculiar construction of the box, which are highly inconvenient and 20 impractical.

The primary and basic object of my invention is to produce a mail box of such a construction that it will consist only of a body part and a door, the door and the body 25 part so constructed that the door can be opened to approximately the entire extent of the mail box, so that the mail can be taken out bodily and not pulled out, thus preventing the tearing of the mail and dispensing with the inconvenience of taking the 30 same from the box.

In order to carry out and describe my invention, I will set forth one specific form thereof.

35 One of the features of my invention consists in stamping the body of the box out of one piece of sheet metal, and, further, in stamping the front or door of the box out of one sheet of sheet metal, and combining them together so that the door will slide upwardly and downwardly enabling the mail to be abstracted without hindrance, without tearing the same, and in a convenient manner.

40 Another feature of my invention consists in placing upon the door a hinged cover for the mail slot, which works along and moves with the box door when it is raised or lowered, or moved out of the way to allow entry 45 to the box.

Another feature of my invention consists in limiting the upward movement of the door so that it will not leave the body of the box.

Still another feature consists in providing 55 a finger hold for raising the sliding door which, at the same time, acts as a limiting means for raising said door, and another feature of my invention consists in forming a practically water tight joint between the 60 sliding door and the body of the box.

Another feature consists in forming the screw holes in the body of the box so that they will be embossed or rounded on the inside, preventing the tearing of the mail, 65 and that they will be flush at the rear so that the box can be readily hung up.

Still another feature consists in having all the parts of the body part and the sliding door rounded so that there are no corners or projections which would in any wise 70 interfere or tear the mail, while it is being taken out of the box, or when the same is inserted by the mail carrier.

My mail box is unique, in construction, 75 and possesses marked utility.

In the accompanying drawing, forming part of this specification:

Fig. 1, is a view in elevation of my new 80 mail box,

Fig. 2, is a section thereof, on the line 1—1 of Fig. 1, the box being hung up in position,

Fig. 3, is a top view, looking down on the 85 box, and

Fig. 4, is a section on the line 4—4 of Fig. 1, to show the joint connection between the body of the box and the sliding door.

The body of the box is formed of the sides 1, 1, top 2, bottom 3, and back 4. This 90 body is provided, along its edge, with an outwardly extending flaring edge, 5, which extends continuously therearound. This edge is rounded as shown at 6, see Fig. 4.

At the bottom the edge 5 is formed into 95 an extending eyelet 7. In the back 4, I stamp holes 8, through which screws or nails 9 pass to hold the mail box in position.

These holes in the inside of the box are embossed or rounded and smooth so as not to 100 rip or tear the letters, and on the outside are flush with the back so that the box can be positioned flush with the door or frame 10, see Fig. 2. The back, sides, edges, top, and bottom and its other parts are all made integral, and this is the preferred form, although I may form it of parts, if desired, 105 and found convenient in practice.

The front of the box is closed by an upwardly and downwardly sliding door 12, provided at the front side with a mail slot 13, a card holder 14, a finger hold 15, and a depending eyelet 16, at the bottom.

A bead as 17 is also stamped into the face of the door, for strength and to enhance the appearance thereof. Along the side edges the sliding door 12 has inwardly turned runway, or elongated guide recesses 18, which are of a V-shape as shown in Fig. 4, and they fit over and run on the edge 5 along the sides of the body of the box, a frictional contact being formed between these two meeting edges, so that no water or moisture can enter the box and to make a double track for the sliding door of the box.

The finger hold 15 is made as shown in Fig. 2, so that a firm hold can be taken by the operator, an outwardly extending rounded flange 19 and an inwardly extending rounded flange 20, forming the same.

All the parts just described as making and forming the sliding door are stamped out of one piece of metal and are therefore formed integral, but I may form said sliding door of parts, if found expedient.

A lid to protect the mail slot 13 is formed of a body 21 having an upper rearwardly extending flange 22, and an outwardly extending flange 23 at its lower extremity. Between the top edge of flange 24 of the sliding door 12 and the rearwardly extending flange 22 on the lid or cover, I form a hinge connection 25, so that the said mail slot, lid or cover can be swung. The upper rearwardly extending flange 24, at the top of the sliding door, when the door is down in position to be locked, abuts against the top of the flaring edge 5 at the upper end of the body part, making a tight joint and forming a species of water shed to prevent the water or moisture from entering the box at the top.

At the top of the box, at its rear, I provide a device for holding newspapers, pamphlets, and the like, which cannot be placed in the box itself. It is marked 30 in the drawing and is preferably of the shape shown therein, having a hole at the bottom through which the screw 9 passes, which holds said device 30 in position, see Fig. 2, however, any form of the device may be used for holding said papers and pamphlets.

When the eyelets 7 and 16 are in juxtaposition, a lock may be placed therethrough for locking the parts together, the lock not being shown. I preferably place the eyelets 7 and 16 and extend them beyond the edge of the body and door as shown for the purpose of providing for a full up and down movement of the door; the object being to have a door which by sliding, swinging, or pivoting, or the like, can be moved in such

a manner that full access will be had for the extraction of the mail in the box from the bottom instead of at the top.

The card holder 14 is formed of rectangular ridge 11 and provided with tangs 14' at each side and at the top, and bottom, and when the name-card is inserted therein said tangs can be tapped to impinge against the name-card and tightly hold it in position.

It will be noted that the body of the box has rounded corners, and its sides, top, and bottom walls are also rounded, allowing facility for removal of the mail, and enhancing the appearance of the box, and also giving facility for stamping the same out of one piece of material.

The rounded flange 20 abuts against the top of the box when the sliding door 12 is raised to its limit, thus preventing the door 12 from leaving the body of the box.

It will be noted that when the sliding door 12 is raised or lowered the mail slot cover travels along with it. If there is any mail in the box, it can be seen through the finger hold 15.

It will be readily seen that this mail box is very simple, convenient and strong, and that by raising the door 12 upwardly the mail can be taken out without tearing the same, because it does not have to be pulled through a top slot or narrow, inconvenient lid, or the like.

While I have described one specific and preferred way of making my mail box, I do not wish to limit myself to the exact construction, as I may change and modify the same to some extent.

What I claim as new and my invention and desire to secure by Letters Patent is:

1. In a mail box of the character described, a body part and a door part, combined together, the door part capable of sliding upwardly and downwardly on the body part, a single hole on the said sliding door part for use in raising said sliding door, and a stop on the door arranged adjacent to said hole to limit the upward movement of the door part.

2. In a mail box of the character described, a body part, having an upwardly extending flange at the top, a sliding door, said sliding door provided at the top with an inwardly extending flange, a mail slot cover attached to said inwardly extending flange so that the said cover will swing, said flange on said sliding door when the sliding door is down passing over the upturned flange on the body part to form a double joint and prevent the entry of the wet elements.

3. In a mail box of the character described, a body part and a sliding door part of substantially equal height, one of said parts being provided at its edge with an outwardly extending continuous flange,

the other part being provided at its side edges with grooves slidably engaging said flange, and at its top with a flange engaging the first mentioned flange, said door part being slideable upwardly beyond the upper edge of the body part to open substantially the entire front of the body part, and a slot in said box to permit mail to be deposited in the same.

10 4. A mail box as claimed in claim 3, in which the lower edges of the body part and door part are extended downwardly to provide tongues, said tongues having registering apertures adapted to receive a padlock.

15 5. A mail box as claimed in claim 3, in which the door part is provided near its lower end with a hand hold, outwardly and inwardly extending lips arranged on the door part adjacent said hand hold, the inwardly extending lip, when the door part is raised, being adapted to engage the top of the body part to limit the movement of the door part.

6. A mail box comprising a body formed of a single piece of metal and having its 25 front face open, the body being provided at its edges with an outwardly extending flange, a sliding door closing the entire front of the body and provided along its side edges with grooves engaging said flange, 30 said door being slideable upwardly beyond the upper edge of the body, a stop arranged on the inner surface of the door near the lower end of the latter, and adapted, when the door is slid upwardly, to engage the top 35 of the body and limit the upward movement of the door, a rearwardly extending flange provided at the upper end of the door and adapted to engage the flange at the top of the body, said door having a slot to permit 40 mail to be deposited in the box, and a cover for said slot hinged to the flange of the door.

In testimony whereof, I affix my signature at Cincinnati, Ohio, this 16th day of February, 1924.

THOMAS B. WRIGHT.
